UNITED STATES PATENT OFFICE

AUGUSTO DINA, OF JERSEY CITY, NEW JERSEY, ASSIGNOR TO INTERNATIONAL PROJECTOR CORPORATION, OF NEW YORK, N. Y., A CORPORATION OF DELAWARE

SWITCH FOR PROJECTION MACHINES

Original application filed May 31, 1928, Serial No. 281,872. Divided and this application filed May 20, 1929. Serial No. 364,371.

This invention relates to electrical switches for projection machines, and more particularly to a new and improved mechanism for operating a switch by foot pressure.

5 This application is a division of my co-pending application, Serial No. 281,872, filed May 31, 1928, for electrical switching apparatus for picture projection machines.

An object of the invention is to provide a 10 foot control for operating an electric switch whereby injury to the switch due to excessive pressure is avoided.

Another object is to provide a foot control mechanism of simplified construction 15 which may be readily applied to a standard type of electric switch.

The invention also consists in certain new and original features of construction and combinations of parts hereinafter set forth 20 and claimed.

Although the novel features which are believed to be characteristic of this invention will be particularly pointed out in the claims 25 appended hereto, the invention itself, as to its objects and advantages, the mode of its operation and the manner of its organization may be better understood by referring to the following description taken in connection with the accompanying drawing forming a 30 part thereof, in which

Fig. 1 is a vertical section of the foot switch;

Fig. 2 is a section on the line 2—2 of Fig. 1; and

Fig. 3 is a transverse section showing the arrangement of the casing with respect to the switch member.

Like reference characters denote like parts in the several figures of the drawing.

40 In the following description and in the claims parts will be identified by specific names for convenience, but they are intended to be as generic in their application to similar parts as the art will permit.

45 Referring to the drawing more in detail, the invention is shown as applied to a foot switch control comprising a casing 2, suitably recessed to receive a switch member 3 of any well known construction. The switch member is provided with a push button 4

which is adapted on successive strokes to alternately open and close the circuit therethrough. The particular form of switch member, however, forms no part of the present invention and will not be described in detail.

Cover 5, which may be secured to casing 2 by screws 6, is provided with a plurality of vertical bores for receiving push rod 7 and plungers 8. The lower portion of push rod 7 is provided with an outwardly extending flange 9 which is adapted to contact with a shoulder 10 on cover 5 to prevent the rod from being entirely withdrawn. Cap 11 is secured to the upper portion of push rod 7 by any suitable means such as pin 12 extending through an extension of said cap and through said push rod. The upper surface of cap 11 may be formed of any desired contour but is preferably of spherical shape as shown in Fig. 1 and formed with a radius extending through push rod 7 above shoulder 9. The force applied to the cap is thus transmitted to push rod 7 at a point where it is supported within cover 5 and the friction of said rod in said cover is reduced to a minimum.

50 Plungers 8 are forced against the lower surface of cap 11 by springs 15 which are retained in the above mentioned recesses in cover 5 by suitable means, such as washer 16. Said washer may be secured to the under-surface of cover 5 by screws 17.

Cover 5 and casing 2 are formed of sufficiently strong material to prevent damage thereto by reason of the foot pressure which is exerted on cap 11. The lower portion of cap 11 contacts with the upper end of cover 5 for limiting the movement of push rod 7 whereby injury to the switch 3, which may be of comparatively delicate construction, is prevented.

55 Switch 3 may be secured in casing 2 by retaining members 18 which are secured to said casing by screws 19 and a strap 20 which is passed over said switch and secured to said switch and to members 18 by screws 21. Switch 3 is seated in a suitable recess in casing 2 and is held by the above described means in alignment with push rod 7. Casing 2 is provided with a pair of openings 25 through

which a conduit (not shown) is applied to switch 3. The casing is also provided with an outwardly extending flange 26 having a plurality of holes 27 therein to facilitate attachment to the floor or other surface.

The particular construction of switch casing disclosed permits a relatively inexpensive switch to be used and eliminates danger of injury thereto. The switch may be conveniently located and may be operated by pressure of the foot which may be applied from any convenient direction on any portion of the cap.

The switch has been shown by way of illustration as having two plungers 8 located on opposite sides of push rod 7. It is obvious, however, that the number of plungers may be varied as desired in accordance with the requirements of a particular case.

20 Springs 15 should be so related to the push rod 7 and cap 11 that they automatically force these elements into raised position when the foot pressure is released, thereby allowing push button 4 to assume its normal position in readiness for another operation. By spacing plungers 8 symmetrically about push rod 7 the push rod is maintained in central position and the sliding friction thereof reduced.

25 The switch is particularly applicable to motion picture projection machines and may be located in a convenient position for foot operation. The form of the casing and cap is such that the switch may be readily located and operated by the foot of the operator in starting and stopping the machine.

30 While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

35 45 What is claimed is:

1. A foot switch control comprising a casing adapted to receive a switch member of the intermittent push type, a cover for said casing having a plurality of bores therein, a push rod in one of said bores and engaging said switch member, an outwardly extending flange on said push rod and a cooperating shoulder on said cover adapted to be engaged thereby for preventing withdrawal of said push rod, a cap secured to said push rod, and spring pressed plungers mounted in others of said bores cooperating with said cap to normally hold said push rod in a raised position.

60 65 2. A foot switch control comprising a casing adapted to receive a switch member of the intermittent push type, a cover for said casing having a plurality of bores therein, a push rod in one of said bores and engaging said switch member, a cap secured to said

push rod, and spring pressed plungers mounted in others of said bores cooperating with said cap to normally hold said push rod in a raised position.

3. A foot switch control comprising a casing adapted to receive a switch member of the intermittent push type, a cover for said casing having a plurality of bores therein, a push rod in one of said bores and engaging said switch member, a cap secured to said push rod, and means mounted in others of said bores cooperating with said cap to normally hold said push rod in a raised position.

4. A foot switch control comprising a casing adapted to receive a switch member of the intermittent push type, a cover for said casing having a plurality of bores therein, a push rod in one of said bores and engaging said switch member, means for preventing withdrawal of said push rod, a cap secured to said push rod, and means mounted in others of said bores cooperating with said cap to normally hold said push rod in a raised position.

5. A control for an intermittent push switch having a push button associated therewith comprising, a casing adapted to surround said switch, a cover supported by said casing and recessed to receive said push button, a push rod slidably held in said cover and adapted to contact with said push button, means for normally holding said push rod in raised position, and means associated with said cover for preventing depression of said push rod beyond a predetermined point.

6. A control for an intermittent push switch having a push button associated therewith comprising, a casing adapted to surround said switch, a cover supported by said casing and recessed to receive said push button, a push rod slidably held in said cover, a cap secured to the top of said push rod, plungers cooperating with the bottom of said cap and springs secured in said cover for normally causing said plungers to exert an upward pressure on said cap.

7. A control for an intermittent push switch having a push button associated therewith comprising, a casing adapted to surround said switch, a cover supported by said casing and recessed to receive said push button, a push rod slidably held in said cover, said push rod having an outwardly extending flange, a shoulder on said cover cooperating therewith to prevent withdrawal of said push rod, and a cap secured to the top of said push rod and adapted to engage said cover for limiting the downward movement thereof.

AUGUSTO DINA.
